United States Patent Office

Des. 224,394
Patented July 25, 1972

224,394

BUILDING STRUCTURE OR THE LIKE

Edgar H. Hunter and Margaret K. Hunter, both of 1108
Manchester Drive, Raleigh, N.C. 27609

Filed Mar. 12, 1970, Ser. No. 21,879

Term of patent 14 years

Int. Cl. D25—03

U.S. Cl. D13—1

FIG. 1

FIG. 2

FIG. 3

FIG. 1 is a top plan view of a building structure or the like, showing our new design;

FIG. 2 is a side elevational view of such design; and

FIG. 3 is a front elevational view thereof.

The rear and side not shown are substantially identical to the corresponding front and side views illustrated.

We claim:

The ornamental design for a building structure or the like, as shown and described.
